UNITED STATES PATENT OFFICE.

OTTO WILLIAM MEISSNER, OF WESTMOUNT, QUEBEC, CANADA.

TRAP-DOOR.

1,022,747.

Specification of Letters Patent.

Patented Apr. 9, 1912.

Application filed November 12, 1907. Serial No. 401,876.

To all whom it may concern:

Be it known that I, Otto WILLIAM MEISSNER, of Westmount, Province of Quebec, Canada, have invented certain new and useful Improvements in Trap-Doors; and I do hereby declare that the following is a full, clear, and exact description of the same.

My invention relates particularly to trap doors for use in controlling the flow of cereals, coal, ore and other loose commodities, although it can be applied, with advantage to other doors requiring to be sealed, and it may be said specifically to consist of a trap door having three sides flanged, a valvular member adapted to close and seal the fourth side, such member being preferably carried by the frame of the door, and means for moving such member to and from sealing position.

For full comprehension, however of my invention reference must be had to the accompanying drawings forming a part of this specification, wherein corresponding reference numerals indicate the same parts, and in which—

Figure 1 is a longitudinal sectional view of a portion of a railway car with my invention applied thereto; and Fig. 2 is a similar view of the door partially open and in the act of being closed. Fig. 3 is a plan view thereof, and Fig. 4 is an underside view of the valvular means for sealing the end of the door. Fig. 5 is a perspective view of the hinge block; and Fig. 6 is a view similar to Fig. 1 with the door full open.

The preferred embodiment of my invention consists of a door *b* provided with laterally projecting flanges *c* on one end and both sides, such door being hinged in a slotted hinge block *d*, while the opening in the door frame is provided with flanges *e* on all four sides, the door being adapted to inclose these flanges *e* except at one end; and that end is closed by a valvular member constituting the principal feature of this invention. This valvular member consists broadly speaking of an angle iron *g* movably supported and adapted to be set in place seal-

ing the free end of the door after the latter is closed. This angle iron is carried and operated by the following means:—A pair of hinged bracket arms *2* are pivoted to the stationary bracket and carry the angle iron at their free ends, while a pair of stationary brackets *4* (mounted upon the frame of the car) support and act as guides for a shaft *5* adapted to be rolled or shoved laterally to and fro along such stationary brackets to lift and retain the said bracket arms *2* and the angle iron, or allow them to drop away from the door opening, such shaft being operated and locked in its supporting position by any preferred means (not shown) usually employed for operating and locking the well known door raising and lowering shaft. The usual door lifting shaft *7* is employed for raising the door and allowing it to descend, and according to this invention the shaft is carried rotatably in brackets *10* upon the door at each side thereof, each end of the shaft being polygonal and projecting as at 25 a short distance beyond the sides of the door, while it is rotated by any suitable wrench or spanner, and ratchet wheels *12* and pawls *13* retain the shaft against unwinding until it is desired to lower the door when the pawls are knocked out of engagement with the ratchet wheel. The trap door *b* when being closed is first raised to position inclosing the depending flanges *e* of the door opening, and held there while the arms *2* with angle iron *g*, are raised to bring the latter into position sealing the open end of the door.

The object of providing the sliding hinge for the door is to allow the rear flange of the latter to remain constantly in bearing relation with the corresponding flange of the door opening and particularly as the door descends to and rests in discharging position, thus preventing leakage at this point both when the door is open and closed. In the latter case this arrangement is particularly serviceable because the rear flange of the door is then brought with its face into tight bearing relation with the flange of the door opening the effect of which is

the perfectly tight closure of that part of the door, the other part being taken care of by the valvular member.

It will be noted that the axis of the hinge 5 for the door is located between the top and bottom edges of the flanges, *e*, of the door opening, thus causing a portion of each side flange of the hinged end of the door to overlap the corresponding portion of the flanges 10 *e* when the door is in its unloading position, and thereby at all times, preventing lateral displacement of the hinged end of the door.

The trap door described herein is applicable to cars as well as to bins or other structures where such a door may be desirable.

What I claim is as follows:—

1. The combination with a trap door having upwardly projecting flanges on opposite sides, of a displaceable flange adapted to project under and close one of the remaining sides of the door, and operating mechanism connected to the flange.

2. The combination with a door having upwardly projecting flanges on three sides 25 to form a trough with one end open, of a valvular member equal in width to such open end and adapted to close the latter and project under and support the door when in closed position and move from the said open 30 end when the door is opened, and means for operating the said member.

3. The combination with a door of trough form with one end open, of an angle strip adapted to project under and close the said 35 open end when the door is closed, and move away from such open end when the door is opened, and means for operating the said strip.

4. The combination with a hinged flanged 40 door one side whereof is without a flange, of a displaceable member consisting of an angle strip one flange whereof is adapted to overlap such side and the other flange whereof is adapted to act as a flange for 45 said nonflanged side when the door is closed.

5. The combination with a door frame having a continuous flange extending around all sides of the door opening, a trap 50 door hinged to the frame and having a continuous flange extending around all the sides thereof except one and adapted to inclose the corresponding portion of the flange of the door opening, and displaceable means 55 for sealing the joint between the remaining portion of the door and the flanged frame.

6. The combination with a door frame having a continuous flange extending around all sides of the door opening, a trap 60 door hinged to the frame and having a continuous flange extending around all the sides thereof except one and adapted to inclose the corresponding portion of the flange of the door opening, an angular member, and

means for swinging the said member to and 65 from position sealing the joint between the non-flanged side of the door and the flanged frame.

7. The combination with the door frame having a continuous flange extending 70 around all sides of the door opening, a trap door hinged to the frame and having a continuous flange extending around all the sides thereof except one and adapted to inclose the corresponding portion of the flange of 75 the door opening, a pair of supporting arms hinged to the frame, an angle iron mounted upon such arms, and means for allowing the said supporting arms to swing and such means supporting the said arms when the 80 door is closed with the angle iron in position sealing the joint between the non-flanged side of the door and the flanged frame.

8. The combination with a door frame 85 presenting a door opening, of a flanged door adapted to register with and substantially close such opening, and a displaceable sealing strip adapted to seal the space between the door and frame.

9. The combination with a flanged door frame presenting a door opening, of a door of trough form with open end adapted to register with and substantially close such opening and displaceable means for sealing 95 the joint between the said open end of the door and the door frame.

10. The combination with a door having three sides flanged to form a door of trough form with open end, of a displaceable member adapted to extend under and to act as 100 a flange for such open end when the door is closed.

11. The combination with a downwardly flanged door frame presenting a door opening, 105 of a hinged door having an upwardly projecting flange extending continuously around its hinged side and the sides adjacent thereto, such flange being adapted to closely inclose the door frame flanges, of a 110 pair of hinged members connecting such door and frame, one of such members being horizontally slotted and the other having a hinge pin movably supported in the said slot, such slot and pin being located at a 115 lower level than the top of the said flange.

12. The combination with a door frame presenting a door opening, of a trap door comprising a main part of trough form, and a part sealing the space between one end of 120 the trough and the door frame, and a shaft movable transversely of its axis relatively to both door parts and adapted to bear against one of such parts and hold both parts closed.

13. The combination with a door frame having flanges extending downwardly on 125 all sides thereof, of a hinged door having

on three of its sides fixed flanges extending upwardly and inclosing the flanges of the corresponding sides of the door frame, and a displaceable angle bar forming a flange for the remaining side of the door, such angle bar overlapping and inclosing the said remaining door side and the adjacent flange of the door frame.

In testimony whereof, I have signed my name to this specification, in the presence of 10 two subscribing witnesses.

OTTO WILLIAM MEISSNER.
